UNITED STATES PATENT OFFICE.

JOHN W. MYERS AND CLARENCE A. MYERS, OF QUINCY, ILLINOIS.

BOX-FASTENER.

SPECIFICATION forming part of Letters Patent No. 593,753, dated November 16, 1897.

Application filed August 30, 1897. Serial No. 649,988. (No model.)

To all whom it may concern:

Be it known that we, JOHN W. MYERS and CLARENCE A. MYERS, citizens of the United States, residing at Quincy, in the county of 5 Adams and State of Illinois, have invented certain new and useful Improvements in Box-Top Fasteners; and we do declare the following to be a full, clear, and exact description of the same, reference being had to the accompanying drawings, forming a part of this specification, and to the letters of reference marked thereon.

This invention relates to improvements in fasteners for the lids or tops of boxes, crates, &c., and is especially designed for fastening the trays of egg-crates; and it has for its object to provide a fastening or lock whereby the tray or lid may be locked at different points of adjustment within the box or crate. 10 To these ends the invention consists in certain novel details of construction and combinations and arrangements of parts, all as will be now described, and the particular features of novelty pointed out in the claims.

20 Referring to the accompanying drawings, Figure 1 is a top plan view of a lid or tray provided with our invention, the device being shown in locked position; Fig. 2, a similar view, the device being in unlocked position. Fig. 3 is a section on the line $x-x$, Fig. 1. Fig. 4 is a longitudinal section on the line $y-y$, Fig. 1.

Similar letters of reference in the several figures indicate the same parts.

25 As illustrated, the letter A indicates the lid or tray of an egg-shipping crate B, which tray fits snugly within the crate. The improved lock or fastener for the lid consists of a piece of wire of suitable size and weight, which is bent or doubled at or near its middle, forming the substantially parallel portion or legs C C, and then continued and bent over to form the handle D. The ends of the wire are bent at substantially right angles to the doubled portion and are carried in opposite directions, forming the arms D' D', which are preferably pointed and pass through transverse apertures in the cleats E E, secured to the lid at each side.

30 Pivoted on the lid so as to swing horizontally is a locking lever or arm F, having an enlarged head or cam projection G at one

end lying between the legs C C of the wire. This head, it will be noted, is wider in one direction than in the other, being preferably 55 elliptical in shape, and is formed with overhanging ears or lugs g g, as shown clearly in Fig. 3. The lever-arm is also provided with a locking stud or projection f, made preferably by striking up the metal of which the 60 arm is formed.

The operation will now be understood. The tray having been placed within the crate with the parts in the position shown in Fig. 2, the lever-arm is thrown to the position shown in 65 Fig. 1. By this operation the legs C C will be spread apart by the head G, thus forcing the arms D' D' outward in opposite directions and causing the pointed ends to penetrate into the sides of the box or crate and hold the 70 lid at the desired place. When the lever-arm is thrown to this locked position, the overhanging lugs will ride over and press upon the legs C C and hold them down and prevent the liability of their being turned up, the projection on the lever-arm passing under and 75 lying between the legs preventing the lever from swinging out sidewise. To unlock the lid, it is only necessary to swing the lever-arm to either side until the head lies with its 80 greater width parallel with the legs C C, when the wire by its resiliency will resume normal position and the points of the arms D' D' will be withdrawn from contact with the box. The lid may then be removed by the handle D. 85

The device, it will be seen, is simple, can be easily and readily applied, and yet constitutes an effectual fastening, not being easily unlocked except when desired.

Having thus fully described our invention, 90 what we claim as new, and desire to secure by Letters Patent, is—

1. The combination with an adjustable box-cover, of a fastener formed of a single piece of wire having the oppositely-extending locking-arms, and central doubled portion, a locking-lever having an enlarged head, working between the legs of the doubled portion, whereby they may be spread; substantially 95 as described.

2. The combination with an adjustable box-cover, of a fastener formed of a single piece of wire, having the oppositely-extending pointed arms for penetrating the receptacle,

and a central doubled portion, a horizontally-pivoted lever having the head wider in one direction than in the other, lying between the legs of the doubled portion, whereby when 5 the lever-head is turned with its wider portion at right angles to said legs, they will be spread apart and the arms caused to penetrate the receptacle; substantially as described.

3. The combination in an adjustable box-
10 cover or the like, of a fastener formed of a single piece of wire bent to form the central doubled portion and oppositely-extending arms, and a lever having an enlarged head lying between the legs of the doubled portion,

and provided with the overhanging lugs; substantially as and for the purpose set forth. 15

4. The combination in an adjustable box-cover of a fastener formed of a single piece of wire bent to form the central doubled portion and oppositely-extending locking-arms, 20 a horizontal pivoted lever, for spreading said arms, and the locking projection carried by said lever; substantially as described.

JOHN W. MYERS.
